UNITED STATES PATENT OFFICE.

CLINTON W. SCHALL, OF COLUMBUS, OHIO.

CONCRETE SHINGLE OR VENEER SLAB.

Application filed January 18, 1926. Serial No. 81,918.

Some forms of block or slab used in building houses have been more or less objectionable because of their tendency to absorb and retain water resulting in a dampness of the interior of the building.

The object of this invention is to provide a suitable and economical form of molded concrete slab or shingle adapted for rapid erection on a frame and also adapted to provide adequate ventilating space between it and the frame to insure interior dryness.

The invention is embodied in the example herein shown and described, the features of novelty being finally claimed.

15 In the accompanying drawing—

Figure 1 is a view in elevation of the slab or shingle at its inner side.

Fig. 2 is a section on the line II—II Fig. 1.

20 Fig. 3 is a vertical section of a wall built up of the slabs on the line III—III, Fig. 4.

Fig. 4 is an elevation of a fraction of wall showing how the slabs are laid.

25 Fig. 5 is a detail view in plan illustrating the hole for receiving the bonding device.

In the views 6 designates the body of the shingle or slab preferably of square contour and hollow like shallow box but slightly wider on the lower flange where the outer corner is provided with a downwardly projecting lip 7 to promptly drain water from the exposed face of the block. The ring of the upper and lower walls or flanges of the slab are provided with projecting studs 8 so as to fix the body of the slab in spaced relation to the surface against which it is placed and thereby leave a free space for the passage of air in all directions beyond the flanges of the slab. The cavity of the slab can be provided with a centrally and vertically located web 6^a. The upper flange of the slab is made with a slot 9 having a circular central portion to receive a bond device 10 of wire or sheet metal.

45 The whole slab and its parts as thus constructed can be molded of concrete in a single mold at one operation. Because made

hollow the slab is light in weight and does not require much material.

50 Referring to Fig. 3 where a fraction of wall built of these slabs is illustrated the character 11 designates the foundation or water table upon which is erected the wooden frame of the building including the usual plate 12, the studding 13 and the sheathing 14. The slabs are applied to the sheathing 14 in veneer form, that is they are laid preferably in cement mortar with the lower or outer edge of the first course 55 fitting on the water table so as to shed water and the subsequent slabs then laid in the same manner with respect to the upper edge of the slabs of the first course. As the slabs are laid they are bonded to the 60 sheathing 14 as the work proceeds. The slabs are preferably laid in break-joint fashion as depicted in Fig. 2, in which case the web 6^a of the slab aligns with the joints both above and below. For the turns or 65 corners in the wall slabs of smaller size are provided for alternate courses.

70 When the wall is completed there is a large free space for air between the veneer and the sheathing thereby preventing the 75 access of moisture to the plaster that is laid upon the interior of the studding.

In practice the blocks are preferably made about one foot square so that they can be easily handled and the veneer or wall 80 quickly erected but the forms and dimensions of the parts can be varied without departing from the gist of the invention as claimed.

85 What I claim is:

A building slab or shingle of concrete consisting of a shallow box-like structure provided with a plurality of studs projecting from the edges of the walls forming the cavity of the box-like structure, said studs 90 being spaced from each other and adapted when the courses of slabs are applied to a sheathing to permit ventilation of the interiors of the slabs both vertically and horizontally.

CLINTON W. SCHALL.
